UNITED STATES PATENT OFFICE.

GEORGE I. ROCKWOOD, OF WORCESTER, MASSACHUSETTS.

AUTOMATIC SPRINKLER SYSTEM.

No. 894,904.

Specification of Letters Patent.

Patented Aug. 4, 1908.

Application filed February 28, 1908. Serial No. 414,194.

To all whom it may concern:

Be it known that I, GEORGE I. ROCKWOOD, a citizen of the United States, residing at Worcester, in the county of Worcester and 5 Commonwealth of Massachusetts, have invented a new and useful Improvement in Automatic Sprinkler Systems, of which the following is a specification, accompanied by drawings forming a part of the same, in 10 which—

Figure 1 represents my improved sprinkler system in elevation. Fig. 2 is a central vertical sectional view of a dry pipe valve embodied in said system.

15 Similar reference letters and figures refer to similar parts in the different views.

The objects of my present invention are to provide means for controlling the water supply to a series of what are known as open 20 sprinkler heads, or sprinkler heads communicating by a permanently open passage with the water supply pipe, and it consists in the construction and arrangement of parts as hereinafter described and pointed out in the 25 annexed claims.

Referring to the accompanying drawings which illustrate the application of my invention to a sprinkler system located in an electric car barn or shed, 1 denotes a water supply pipe leading to a source of water supply under pressure.

2 denotes the casing of a dry pipe valve, and 3 a pipe leading from the casing of the dry pipe valve to a sprinkler supply pipe 4, 35 upon which are mounted one or more closed sprinklers of any approved type, capable of being released by the action of a predetermined degree of heat. Normally the passages in the sprinkler 5 are closed to the passage of water and the system, comprising the pipes 3 and 4 and sprinklers 5, is closed and normally filled with air under pressure, sufficient to hold the dry pipe valve closed against the pressure of water in the supply pipe 1.

40 In Fig. 2 I have shown a central sectional view of a dry pipe valve inclosed in the case 2, and consisting of a valve plate 6 connected with a rocking arm pivoted at 7 and seated upon annular valve seats 8 and 9, the valve 45 seat 9 being of much smaller diameter than the seat 8 and closing the water passage through the pipe 1, while the valve seat 8 receives the pressure of the compressed air filling the dry pipe valve case and pipes 3 and 4, 50 the difference in the areas inclosed by the valve seats 8 and 9 enabling a given water

pressure in the pipe 1 to be resisted by a smaller air pressure in the sprinkler system.

The above described arrangement of a water supply pipe, closed sprinkler system and 60 dry pipe valve is substantially like that now in use, with automatic sprinkler heads, adapted to be released by the action of heat, and until so released serve to maintain a constant air pressure upon the dry pipe valve to 65 hold it in contact with the seats 8 and 9.

Between the valve seats 8 and 9 is an inclosed annular space 10 cut off from the pressure of compressed air in the dry pipe valve casing, when the valve is closed, by the valve 70 seat 8 and also from the water pressure in the pipe 1 by the valve seat 9. The annular space 10 will, therefore, be filled with air at atmospheric pressure. Communicating with the air space 10 is a pipe 11 leading to a sprinkler supply pipe 12, upon which is mounted a series of open sprinkler heads 13, of any known or approved type. In Fig. 1 the pipe 12 is placed horizontally by the side of a car 14, while the supply pipe 4 is preferably 80 placed in an elevated position above the car. If either one of the sprinkler heads 5 be released by the action of heat, the compressed air held in the pipes 3 and 4 will be allowed to escape, and the pressure of water 85 in the pipe 1 will immediately raise the valve plate 6 from its seats 8 and 9, and not only admit water to the pipes 3 and 4, but also fill in the annular space 10 and the pipes 11 and 12 with water under pressure, which is directed in sprays against the sides of the car 14 by the open sprinkler heads 13. The open 90 sprinkler heads 13 may be placed in positions where their use will be most effective, while the closed sprinkler head on the pipe 4 may 95 be placed in a position where heat will be most effective in releasing it. The entire system of open sprinklers connected with the dry pipe valve through the pipe 11 will also be brought into service by the release of any 100 single sprinkler head on the pipe 4, which opens the passage sufficient to release the pressure upon the valve plate 6 and allow the pressure of water in the pipe 1 to raise the valve plate from its seats. Unless the heat 105 is sufficiently diffused to release a large number of the closed sprinkler heads on the pipe 4, the amount of water distributed by the pipe 4 will be restricted to the one or more 110 sprinkler heads which have been released by heat, while the larger body of water will be delivered through the open sprinkler heads

13 and directly upon the conflagration occurring in the car 14. If desired, the number of sprinkler heads upon the pipe 4 may be limited to such number and in such positions as 5 will be sufficient to control the flow of water through the open sprinklers, thereby reducing the liability of damage from water by over flooding, while the water delivered through the open sprinklers may be applied 10 directly into the fire from the side.

I have not deemed it necessary to show and describe in detail the construction of what are known as closed and open sprinkler heads, such devices are now in common use 15 and will be well understood by those conversant with the art of automatic sprinkling. By my improved system employing open sprinkler heads for the distribution of water, and closed sprinkler heads primarily for controlling the flow of water to the open sprinklers, I reduce the amount of piping and fittings inclosing the body of compressed air, and thereby reduce the liability of leakage of the compressed air and at the same time reducing the volume of compressed air necessary to hold the dry pipe valve closed. 20 25

I claim,

1. In a sprinkler system, the combination with a water pipe communicating with a 30 source of supply under pressure, a supply pipe leading therefrom to a series of closed sprinkler heads, a second supply pipe leading therefrom to a series of open sprinkler heads, a valve for closing the water from both of 35 said supply pipes, and means controlled by said closed sprinkler heads for maintaining an air pressure on said valve to hold it closed.

2. In a sprinkler system, comprising a series of open sprinkler heads, and a series of 40 closed sprinkler heads adapted to be opened

by the action of heat, a water supply pipe having a valve closed communication with both of said series of sprinkler heads, and means for holding said valve in a closed position, and means for releasing said valve 45 controlled by the action of heat upon said closed sprinkler heads.

3. In a sprinkler system, the combination of a series of open sprinkler heads and a series of closed sprinkler heads at a higher level 50 than said open sprinkler heads, supply pipes for both series of sprinkler heads communicating with a common supply pipe, a valve for closing said common supply pipe, means for holding said valve in a closed position, 55 and means for releasing said valve by the action of heat on said closed sprinkler heads.

4. In a sprinkler system, the combination with a water pipe communicating with a source of supply under pressure, of a pipe 60 leading therefrom to a closed sprinkler head, a second pipe leading therefrom to an open sprinkler head, and means for closing both of said supply pipes, said means arranged to be opened by the action of heat on said sprinkler head. 65

5. In a sprinkler system, the combination with a pipe filled with water under pressure, of a supply pipe leading therefrom to a closed sprinkler head filled with air under pressure, 70 a second supply pipe leading therefrom to an open sprinkler head, a valve arranged to close both of said supply pipes, and means operated by the action of heat upon said closed sprinkler head for opening said valve. 75

GEORGE I. ROCKWOOD.
